MOUNTING FOR A REAR VIEW MIRROR

Frederic P. Plotkin, Los Angeles, Calif.

Application September 4, 1959, Serial No. 57,432

Term of patent 14 years

(Cl. D14—6)

Fig. 1.

Fig. 2.

Fig. 3.

Fig. 4.

Fig. 1 is a rear view of a mounting for a rear view mirror showing my new design;

Fig. 2 is a side elevational view thereof;

Fig. 3 is a front elevational view thereof; and

Fig. 4 is a top plan view thereof.

The dominant features of my design reside in the portions shown in full lines.

I claim:

The ornamental design for a mounting for a rear view mirror, substantially as shown and described.
